UNITED STATES PATENT OFFICE.

DAVID D. CLARKE, OF NEWCASTLE, PENNSYLVANIA.

TINNING-MACHINE.

SPECIFICATION forming part of Letters Patent No. 784,836, dated March 14, 1905.

Application filed March 5, 1904. Serial No. 196,785.

To all whom it may concern:

Be it known that I, DAVID D. CLARKE, a citizen of the United States of America, residing at Newcastle, in the county of Lawrence and State of Pennsylvania, have invented certain new and useful Improvements in Tinning-Machines, of which the following is a specification, reference being had therein to the accompanying drawings.

10 This invention has relation to tinning-machines, and has for its object the provision of means for maintaining the palm-oil used in the tinning operation at the proper temperature. In machines of this class the palm-oil 15 is usually maintained in a receptacle which contains molten metal, the oil, commonly called "grease," floating on the molten metal and being maintained in a highly-heated condition by the heat derived from such molten 20 metal. Under these conditions it frequently happens that the oil becomes heated to such a degree that it is burned, and the burned oil adhering to the plates damages or spoils them.

In carrying my invention into effect I arrange in that part of the apparatus containing the oil a series of water-pipes disposed on both sides of the rolls through which the plates pass, and I provide water inlet and outlet pipes connected to the pipes arranged in 30 the oil-receptacle and force water through the pipes in such receptacle, whereby I am enabled to maintain the palm-oil at the proper degree of heat necessary for a perfect carrying out of the tinning process.

35 My invention consist in the novel construction, combination, and arrangement of parts to be hereinafter more fully described and claimed.

In the drawings, Figure 1 is a vertical sectional view of a tinning-machine provided with my improvements. Fig. 2 is a vertical transverse sectional view on the line $x-x$ of Fig. 1. Fig. 3 is a plan view, part of the tin pot or vessel being broken away.

45 The tin is maintained in a molten condition in the vessel 1, which is provided with the usual bell-mouth perforated conduit 2, by means of which the plates to be tinned are directed to and through the partition 3, which 50 is formed with a slot 4, through which the

plates are passed into the extension 5 of the vessel 1. The extension 5 is enlarged from a point in alinement with the top of the vessel 1 and contains rollers 6 6, arranged in pairs disposed one apart from the other, and in the lower part of the extension 5 a curved perforated conduit 7 is arranged, by means of which the plates are conveyed from slot in partition 3 to between rollers 6 6. These rollers are supported in bearings 6', which are supported on brackets 6", which are secured to the top of the vessel 1 and project down and into the vessel to support the bearing 6'. Upon one side of the rollers 6 6 is arranged a sinuous line of pipe 8, which extends substantially from end to end of the rollers and from a point near the top of the upper pair to a point about on a level with the bottom of the lower pair of rollers, this line of pipe being so arranged as not to interfere with or touch the metal, and upon the opposite side of the rollers I arrange a similar line of pipe 9. The lower terminal of the line of pipe 8 is connected at 10 to a horizontal pipe 11, that leads to a vertical pipe 12, 75 that is connected to a horizontal pipe 13, leading to water-inlet 14, the latter being provided with a union-joint 15 and stop-cock 16. The sinuous pipes 8 are suitably braced by the rods 28 to the vertical pipe 12, as shown. Sufficient space is provided between the vertical pipes 12 and the sinuous pipes to permit the insertion of a dipper, whereby the metal may be skimmed without removing the pipes. The line of pipe 9 is connected at 17 with a horizontal pipe 18, that leads to a vertical pipe 19, that is connected at 20 to the inlet-pipe 14, and between this connection 20 and the pipe 14 I provide a stop-cock, as designated at 16', and upon the pipe 13 is located another 90 one of these cocks 16' to control the inlet to the line of pipe 8. The sinuous pipes are attached to the vertical pipes 19 by braces 29, and the horizontal pipes 11 18 are, it will be observed, disposed in the same plane as the lowermost bend or leg of the sinuous line of pipes and on the outside thereof, the purpose of this arrangement being to cause the incoming water to pass first through the pipes 11 18, which are farther away from the rollers 100

than the sinuous lines of pipe 8 9, so that the water will be heated to a certain extent before it reaches the pipes 8 9 adjacent to the rollers 6 6, such arrangement of pipes being devised for the purpose of avoiding the possible chilling of the oil which surrounds the rollers, this chilling causing the metal to adhere or freeze on the rollers.

The upper terminals of the sinuous pipes 10 11 18 are connected by their vertical branches 21 22 to an outlet-pipe 23, leading to a waste-pipe 24. The rollers 6 6 are actuated by gear-wheels 25, arranged on the ends of their shafts outside their bearings, and receive motion from 15 the pulley 26, to which motion is communicated from any suitable source. Each of the vertical pipes 12 and 19 and each of the vertical pipes 21 22 is provided with a protective coating 27 at the point where these pipes pass 20 into and out of the palm-oil, the level of the latter being indicated by the line O O, such protective coating being either formed integral with the pipes, in which event it consists 25 merely of a thickening of the walls of the same, or it may be separately applied to the pipes, as desired, the purpose of coating the pipes at this point being to prevent the pipes from being eaten through by the action of the palm-oil, which when heated attacks the iron 30 of which the pipes are composed at or near the surface of the oil.

The operation of the above-described apparatus is as follows: The pot or vessel 1 is kept filled with metal, which is maintained in molten 35 ten condition to or about the level of the dotted line T T of Fig. 1, and the palm-oil floats on the surface of the molten metal in the extension 5 and surrounds the rollers 6 and the water-pipes in said extension. The plates to 40 be coated are passed through conduit 2 to the slot 4 in partition 3 into the conduit 7, by means of which they are guided to the rollers 6, passing upwardly between the same and through the palm-oil by which the rolls are 45 surrounded. The inlet-pipe 14 is connected to a suitable source of supply, and the cock 16 being open water is allowed to flow through the several pipes above described and find exit through the pipe 23 to the waste-pipe 24. 50 The water coming into the extension 5 first through the vertical pipes 12 and 19 and the horizontal pipes 11 and 18 is heated to a degree sufficient to prevent it from cooling the palm-oil adjacent to the rollers, causing the 55 metal to adhere to a deleterious degree, and

by regulating the supply of water through the cocks 16 16 I am enabled to maintain the palm-oil at just the proper temperature required for the successful accomplishment of the tinning process.

It will be observed from the foregoing description, taken in connection with the drawings, that I have overcome the disadvantage heretofore realized from tinning-machines now in operation and have constructed a machine of the above type which will keep the temperature of the palm-oil at any desired degree of temperature, and I have so constructed this machine that all parts of it will be accessible to the man operating the same, and 60 while I have herein shown and described a specific construction it is obvious that I may change the general arrangement and construction of the pipes without departing from the general spirit and scope of the invention. 65 70 75

Having fully described my invention, what I claim as new, and desire to secure by Letters Patent, is—

1. In a tinning-machine, the combination with an oil-receptacle and rollers arranged 80 therein, of two sinuous lines of pipes arranged one on each side of the rollers in said receptacle, an inlet-pipe and outlet-pipe, both said lines of pipes being connected to common inlet and outlet pipes and the outlet-pipe being 85 provided with protective coverings arranged at the level of the oil in said receptacle.

2. In a tinning-machine, the combination with an oil-receptacle and with rollers arranged therein, of two sinuous lines of pipes, a pipe 90 arranged horizontally on the outside of and spaced apart from and parallel to the lower-most line of each of said sinuous lines of pipes and connected thereto, an inlet-pipe common to said horizontal pipes, said horizontal pipes 95 being connected to said common inlet-pipe, substantially as described.

3. In a tinning-machine, the combination of an oil-receptacle and rollers arranged in said receptacle, with cooling-pipes arranged in said 100 receptacle, inlet and outlet pipes connected to said cooling-pipes and protective coverings arranged on said inlet and outlet pipes at the level of the oil in the receptacle.

In testimony whereof I affix my signature in 105 the presence of two witnesses.

DAVID D. CLARKE.
